UNITED STATES PATENT OFFICE

2,476,398

SWIVEL CONNECTOR FOR ELECTRIC CORDS

Ross Baumann, Bakersfield, Calif.

Application October 3, 1947, Serial No. 777,628

2 Claims. (Cl. 173—324)

1

The object of the present invention is to provide a swivel type electrical connector for use in electric cords, such as those commonly employed upon electric irons, toasters, coffee percolators, curling irons and many other electrical appliances. The twisting and kinking of the cords employed is not only a source of great annoyance but constitutes a source of danger, since the resultant rapid wearing of the cords frequently results in short circuits and costly fires.

My invention not only prevents such kinking in the case of circuits employing only two wires in the electric cord, but also contemplates the provision of an electrical connector which will accommodate cords having three or even more wires in the sheath making up the cord. Cords of this latter nature are commonly employed in connection with telephone mouth pieces. The invention will be best understood by reference to the accompanying drawings wherein:

Fig. 1 is a side view of a swivel connector of the type used on iron or toaster cords, having only two conductors in the enclosed sheath thereof and with the several parts in exploded or separated relation;

Fig. 2 is a sectional view of the structure of Fig. 4; and

Fig. 3 is an inner end elevation of one of the halves of the swivel connection, showing the ball thrust bearing hereinafter described, in place.

Like numerals designate corresponding parts throughout the several figures of the drawings.

In the form of the invention illustrated in the drawing, a casing of hard rubber or other suitable insulating material comprises the two main portions 30 and 31. The two halves of the cable to be connected are indicated at 12b and 12c and these cables comprise two wires. The cup-like casing section 30 of insulating material has an inner lining 32 of relatively thin metal grooved to constitute a screw thread and inturned at the outer end of the member 30 to provide a flange 33. A cap 34 has a threaded portion 35 which screws into a threaded extension 36 of a metallic cap 37. This cap is carried by a porcelain plug 38 and an extension 39 of said cap carries a binding screw 40, to which one of the wires 41, of cable 12b, is connected. The other wire 42 of said cable leads to a central circular contact disk 43 of metal which projects beyond the end of the porcelain block or plug 38 and is held in place by a screw 44. The cap 34 and the parts carried thereby are drawn against the flange 33 of the lining 32 and thus the porcelain plug 38 and its associated parts are held in engagement

5 with said member 30, and the metallic cap 37 establishes electrical connection between wire 41 and inner lining 32. However this engagement is not tight enough to prevent the cap 34, plug 38 and cable 12b from turning as presently set forth.

10 A porcelain plug 46 similar to plug 38 carries a metal cap 47. An extension 48 of this cap carries a binding screw 49 to which one of the wires 50 of cable 12c is connected. The other wire 51 of said cable is connected to a screw 52 and this screw binds a circular central contact disk 53 in place upon the end of the plug 46.

15 The member 31 of the casing has an inner lining consisting of a thin metallic spirally grooved shell 54 the outer end of which is spun over and forms a seat for a leather or other suitable friction ring 55. A second and shorter metallic shell 56 is located in the shell 54 and is inturned to provide an inturned shoulder having a terminal flange 57 which holds the ring 55 in place. A cap 58 has a threaded extension 59 that is 20 adapted to engage within the threaded extension 60 of the cap plate 47 of the plug 46 and when these two parts are screwed together the face 25 61 of cap 58 bears upon the ring 55 and the shoulder 62 of cap 47 bears upon the inturned shoulder of shell 56. These threaded parts 59 and 60 are of such nature that when the cap 58 is 30 screwed up as far as possible against ring 55 the plug 46 and the parts carried thereby are bound against turning in the casing portion 31. But when cap 34 is screwed up as far as possible, the fit is such that the said plug may rotate with 35 respect to the casing portion 30, cap 34 then turning upon the smooth face presented by flange 33.

40 To keep the parts properly aligned, to prevent binding and to make the rotation described an easy one a thrust bearing consisting of ring 63 and balls 64 is disposed between the two plugs 38 and 46. A central opening 65 of the ring 63 fits snugly about the contact disks 43 and 53. That portion of the shell or sleeve 54 which projects inwardly beyond the portion 31 of the insulating casing makes threaded engagement with the correspondingly threaded lining 32 of the portion or member 30 and when these parts are 45 screwed together, the disks 43 and 53 are drawn into easy contact with each other and thus an electrical connection is established. This connection is further enlarged by the fact that the thrust bearing itself, which is of metal, engages these two central contacts, holds them in alignment and facilitates the rotation of the plugs with respect to each other. The electrical con-

nection is through lining 32, shell 54, shell 56, flange 51, metallic cap 41 and binding screw 49 to wire 50.

It will of course be understood that in the case of Figs. 1 and 2 one side of the circuit is completed through one contact disk 43 to the other contact disk 53, facilitated by the presence of the thrust bearing. It is clear that there must not be any contact between the thrust bearing 63 and the sleeve or lining 54 and by referring to Fig. 3 it will be seen that the thrust bearing is enough smaller in diameter than said sleeve to leave ample clearance therebetween.

I wish it to be understood that the invention is not limited to the precise construction set forth but includes within its purview whatever changes fairly come within either the terms or the spirit of the appended claims:

Having described my invention what I claim is:

1. In a swivel connector of the character described, the combination with a two part tubular casing of insulating material of an electrical two conductor cable leading into opposite ends thereof, a block of porcelain or like insulating material for each cable, a metallic cap for each of said blocks, one of the wires of each cable being attached to the corresponding metallic cap, metallic shells within the two part casing having threaded engagement with each other and having electrical engagement with said caps of the blocks whereby a circuit is completed through one side of the circuit, fixed central circular contact discs projecting beyond the confronting ends of the blocks to which the ends of the wires constituting the other side of the circuit are connected, and an anti-friction thrust bearing disposed between the confronting ends of said blocks, and comprising a ring having a central opening dimensioned to fit closely around said discs and to overlap and align both of them and a plurality of anti-friction balls carried by said ring and bearing between the confronting ends of said blocks, the thickness of the ring being less than the diameter of the balls, whereby the ring is out of contact with the blocks but holds the discs and blocks in alignment with each other.

2. In a swivel connector of the character described, the combination with a two part casing of insulating material, each of said parts comprising a sleeve-like member, of a pair of two

conductor cables leading into the opposite ends thereof, a block of insulating material to which the wires of the said cables are connected, the connection for one of the wires of each of said cables to its associated insulating block comprising a metallic cap disposed at the outward end of said block, and an outwardly extending threaded extension carried by each of said metallic caps, a cap of insulating material having threaded engagement with each of said threaded extensions, means for uniting the two halves of the casing consisting of thin metallic threaded shells within the casing which have threaded engagement with each other, one of said shells being carried by each of the casing halves, the said metallic shell of one half being bound into electrical contact with the metallic cap of the porcelain block associated therewith and the metallic shell of the other half having electrical contact with the metallic cap of its associated insulating block, said block being capable of rotation with respect thereto, binding posts carried by the metallic caps of the insulating blocks to which one of the wires of the electric cables are connected, the other wires of said electric cables leading centrally through said blocks to central contact members comprising circular metallic discs which project beyond the confronting ends of the insulating blocks, a ring of metallic material of a width to overlap and align the said discs while permitting rotation of said discs with respect to each other, and anti-friction balls carried by said ring of a diameter greater than the thickness of said ring, as and for the purposes set forth.

ROSS BAUMANN.
